I. C. GELLMAN

ADJUSTABLE SOCKET WRENCH

Filed Feb. 4, 1922

Inventor:

Israel C. Gellman

By: Ernest E. Peeples, Atty.

UNITED STATES PATENT OFFICE.

ISRAEL C. GELLMAN, OF CHICAGO, ILLINOIS.

ADJUSTABLE SOCKET WRENCH.

Application filed February 4, 1922. Serial No. 534,014.

To all whom it may concern:

Be it known that I, ISRAEL C. GELLMAN, a citizen of the United States, residing at Chicago, in the county of Cook and State of Illinois, have invented a certain new and useful Improvement in Adjustable Socket Wrenches, of which the following is a full, clear, concise, and exact description, reference being had to the accompanying drawings, forming a part of this specification.

This invention relates to improvements in wrenches, and more particularly to socket wrenches.

One of the objects of this invention is to provide a socket wrench that adjusts itself to bolts or nuts of various sizes by means of the longitudinal pressure exerted on the wrench by the operator.

Another object is to provide a wrench having separably movable independent jaw members mounted on the wrench so that the motion of the jaw members relative to the wrench is what is technically termed "motion of rectilinear translation," by which is meant that all particles of the body in motion move with equal velocity in paths that are parallel right lines.

Another object is to provide a wrench in which the gripping pressure of the jaws varies with the pressure exerted by the operator longitudinally to the wrench.

Another object of the invention is to provide a socket wrench adapted to operatively engage nuts or bolts positioned in narrow contracted spaces.

Another object is to provide a wrench constructed of a minimum number of pairs of interchangeable members.

Another object is to generally improve wrenches.

Other objects and advantages will herein-after appear.

The invention will be explained and more readily understood when read in conjunction with the accompanying drawings, which illustrate some of the embodiments of which the invention is susceptible, and in which—

Fig. 1 is an elevation of the preferred embodiment of the invention;

Fig. 2 is a perspective view of a portion of the head member shown in Fig. 1;

Fig. 3 is a perspective view of one of the jaws shown in Fig. 1;

Fig. 4 is a slightly modified form of the embodiment shown in Fig. 1;

Fig. 5 is an elevation of a portion of an alternative embodiment of the invention;

Fig. 6 is a side elevation of a portion of the structure shown in Fig. 5;

Fig. 7 is a top plan of the structure shown in Fig. 6;

Fig. 8 is a section along the line 8—8 of Fig. 6;

Fig. 9 is an elevation of another alternative embodiment of the invention; and

Fig. 10 is a partial view on the line 10—10 of Fig. 9.

Similar characters designate like parts in all of the figures of the drawings.

Referring to the drawings, Figs. 1, 2, 3 and 4 show a socket wrench having a head member 2 which is symmetrical about the longitudinal axis α — α of the wrench and is preferably constructed of two interchangeable head sections 3, rigidly fastened together by rivets 4.

A pair of interchangeable jaw members 5 are mounted on head member 2. Each of the jaw members has a shank 6 mounted in a diagonal groove 7 formed in the corresponding section 3. Grooves 7 preferably have an angular cross section and extend diagonally to and intersect on the longitudinal axis of the wrench, so as to be symmetrical about the axis. Shank 6 fits closely in groove 7 and is adapted to move therein only in a direction longitudinal of the groove, sliding over the corresponding face of the shank 6 of the other of the jaw members 5, so that the motion of the jaw member relative to the head member is that known as rectilinear translation.

The inner end of shank 6 is provided with a lug 8 positioned in a groove 7a of the complementary head section and which acts as a stop to limit the outward movement of the jaw member 5 by striking against the face 9 of the other jaw member. Inward movement of the jaw member is stopped by the inner end of shank 6 coming into contact with the inner end of groove 7. Jaw members 5 have their outer ends turned at an angle to shanks 6 so as to form gripping jaws 10 substantially parallel to the longitudinal axis of the wrench. Angular recesses 11 are provided in jaws 10 to engage

nuts, bolt heads or other articles to be gripped by the jaws. The walls 12 of recesses 11 are preferably made parallel to the longitudinal axis, but may be slightly inclined thereto.

It is obvious that movement of the jaw members inwardly and outwardly in grooves 7 moves the jaws 10 respectively towards and away from the longitudinal axis and that walls 12 remain constantly parallel to or with a constant angular inclination to the axis for all positions of the jaw members.

In Fig. 1 the jaw members are shown positioned at their extreme outer position with the jaws 10 spread to their maximum capacity. In this position the jaws occupy approximately the same space as the head, thereby enabling the wrench to be inserted in contracted spaces and to operatively engage bolts positioned therein.

Movement of the jaw members to their extreme inner position brings the jaws into contact as shown in dotted lines in Fig. 1, in which position the jaws grip nuts or bolt heads of minimum size. While head member 2 is adapted to enter relatively narrow openings, it is evident that the jaws in their positions of minimum spread are adapted to enter extremely narrow spaces and engage nuts positioned therein.

Jaws 10 are each yieldingly held in their extreme outer positions by a coiled spring 15 which has one end mounted in an aperture 16 in section 3 and the other in a groove 17 formed in the upper end of shank 6. These springs permit either simultaneous or separate movement of the two jaw members.

A handle 18 is preferably removably mounted in a socket 19 in head member 2 and can be constructed of the form shown or of any other convenient form and made of any desired length.

The wrench is operated by placing the outer end over the nut to be engaged and pressing outwardly, thereby producing an inward longitudinal thrust on jaws 10 sufficient to overcome the outward pressure of springs 15 and to move the jaw members inwardly in grooves 7. This inward movement of the jaw members moves the jaws towards each other until the walls 12 engage the sides of the bolt or nut. The walls 12 being constantly parallel to the longitudinal axis α — α causes the jaws 10 to grip the entire face of the nut, thus avoiding any tendency of the jaws to slip off of the nut when twisting or torsional force is applied to the wrench. Wrenches having jaws whose gripping faces have a varying inclination to the axis of the wrench are particularly susceptible to slipping off of the nuts. Considerable torsional force must be exerted to start tight fitting nuts and a slipping of the wrench necessarily wears off the sharp edges and otherwise mars the nuts so that it is difficult

for a non parallel jaw to engage and hold the same.

In this invention the gripping force of the jaws varies with the outward thrust of the operator and advantage is taken of the fact that the operator usually exerts an outward pressure proportional to the torsional or twisting force necessary to turn the bolt or nut so that the gripping force of the jaws on the nut can be increased with other than the strength of the operator. By utilizing this principle in combination with gripping jaws constantly parallel to the axis, a wrench, adjustable to nuts of varying sizes and with no tendency to slip, has been provided.

In Fig. 4 is shown a slightly modified form of wrench in which the springs 18 are omitted. A coiled spring 22 is mounted in a recess 23, formed in shank 6, with one end of spring 22 in sliding contact with the wall of groove 7. Spring 22, by its resiliency, yieldingly holds the jaw member in any position in which it may be placed and permits movement of the jaw member outwardly and inwardly in groove 7 with lug 8 moving in the corresponding groove 7^a. Jaws 10 are brought into engagement with the nut or bolt by pressure exerted on the jaws in a manner similar to the embodiment shown in Figs. 1, 2 and 3. Upon release of the pressure, the jaws remain stationary and retain contact with the nut so that it can be removed from or placed upon a bolt positioned in an otherwise inaccessible space.

In Figs. 5, 6, 7 and 8 is shown an alternative embodiment differing from the preferred embodiment in that a single spring member 25 mounted on a dog 32 is substituted for the springs 15. Each end of spring member 25 has a tangentially extended straight portion 26 pressing against the inner end of shank 6 so that the jaw members are yieldingly held in their extreme outward position by the resiliency of the spring member 25.

In Figs. 9 and 10 is shown still another alternative embodiment of my invention. A handle member 27 has formed on its outer end, preferably by forging, a forked head member comprising two prongs 28 on which are slidably mounted jaw members 29. Jaw members 29 are cored out to fit over prongs 28 and are held against rotation by pins 30 which are mounted on the outer end of each prong and project therefrom sufficiently to serve as a stop to limit the outer movement of and prevent rotation of jaw members 29. Coiled springs 31 hold the jaw members 29 yieldingly in their extreme outer position in a manner identical with the other embodiments of the invention as illustrated.

Thus it will be seen that an adjustable socket member has been provided having jaws whose gripping faces remain parallel

to or have a constant inclination to the axis of the wrench for all positions of the jaws and resilient means actuating the jaws with each of said jaws movable independently of the other, and which can be economically constructed by reason of its being composed of a few simple interchangeable parts.

I claim:

1. In a wrench of the class described, a head member intersecting having grooves therein and independent separably movable jaw members mounted on the head member and independently movable in the grooves.

2. In a wrench of the class described, a head member having a pair of diagonally extending intersecting grooves formed therein, jaw member reciprocally movable in said grooves, the movement of said jaw members being limited to rectilinear translation and springs controlling the jaw members.

3. In a wrench of the class described, a head member intersecting having grooves therein and independent separably movable jaw members mounted on the head member and separate resilient means actuating the jaw members independently in the grooves.

4. In a wrench of the class described, a head member having a pair of diagonally extending grooves formed therein, jaw members reciprocally movable in the grooves to open and closed position, the movement of the jaw members being limited to rectilinear translation, springs positioned in each of the grooves to yieldingly hold the jaw members in their open position and a lug formed on the inner end of each jaw member that engages a face of the other jaw member when the first jaw member is in its open position.

5. In a wrench of the class described, a head member having independent separably movable jaw members mounted thereon each of said jaw members having a pair of gripping faces parallel to the longitudinal axis of the wrench for all positions of the jaw members, the movement of said jaw members being limited to that of rectilinear translation, and spring means for controlling the jaw members.

6. In a wrench of the class described, a head member having a pair of independent separably movable jaw members mounted thereon, said jaw members each having a pair of gripping faces parallel to the longitudinal axis of the wrench for all positions of the jaw members and resilient means controlling movement of the jaw members relative to the head member.

7. In a wrench of the class described, a head member having grooves adapted for mounting movable jaw members therein, said jaw members having gripping faces parallel to the longitudinal axis of the wrench for all positions of the jaw mem-

bers, and resilient means independently actuating the jaw members in their respective grooves.

8. In a wrench of the class described, a head member having intersecting rectangular grooves and independent separably movable jaw members mounted therein, said jaw members closely fitting said grooves and having gripping faces parallel to the longitudinal axis of the wrench for all positions of the jaw members and resilient means actuating the jaw members independently in their respective grooves.

9. In a wrench of the class described, a head member having intersecting grooves and independent movable jaw members separably mounted therein, said jaw members having a pair of gripping faces parallel to the longitudinal axis of the wrench for all positions of the jaw members and resilient means actuating the jaw members outwardly and yieldingly holding the jaw members in their extreme outward position.

10. In a wrench of the class described, a head member having diagonally extending intersecting rectangular grooves formed therein, jaw members reciprocally movable in said grooves to a sliding fit, the movement of said jaw members being limited to rectilinear translation, springs yieldingly holding each of the jaw members in its extreme outer position, and a lug on the inner end of each jaw member which limits the outward movement of the jaw members.

11. In a wrench, a head member having a pair of movable jaw members mounted thereon, each of said jaw members having a pair of gripping faces constantly parallel to the longitudinal axis of the wrench for all positions of the jaw members, and resilient means actuating the jaw members to open the same, said jaw members being so mounted that an inward thrust on the ends thereof tends to close the jaw members.

12. A wrench of the class described, comprising a head member symmetrical about the longitudinal axis of the wrench and having a pair of intersecting diagonally extending sockets formed in said head member, a pair of independently movable jaw members mounted in the sockets, said jaw members having jaws projecting from the outer end of the head member with gripping faces parallel to the longitudinal axis of the wrench for all positions of the jaws, and a handle mounted on the inner end of the head member.

13. A wrench of the class described, comprising a head member symmetrical about the longitudinal axis of the wrench and having a pair of diagonally extending sockets formed in said head member, a pair of independently movable jaw members mounted in the sockets, said jaw members having

jaws projecting from the outer end of the head member with gripping faces parallel to the longitudinal axis of the wrench for all positions of the jaws, resilient means controlling the jaw members, and a handle removably mounted on the inner end of the head member.

14. A wrench of the class described, comprising a head member symmetrical about the longitudinal axis of the wrench and having a pair of diagonally extending sockets formed in said head member, a pair of independently movable jaw members mounted in the sockets, said jaw members having jaws projecting from the outer end of the head member with gripping faces parallel to the longitudinal axis of the wrench for all positions of the jaws, resilient means mounted in the sockets and yieldingly holding said jaw members in their extreme outward position, and a handle mounted on the inner end of the head member.

15. In a wrench of the class described, a head member symmetrical about the longitudinal axis of the wrench, and having a pair of diagonally extending sockets formed

therein and intersecting on the longitudinal axis of the wrench, said head member comprising two interchangeable sections rigidly fastened together, a pair of independently movable interchangeable jaw members mounted in the sockets, said jaw members having jaws projecting from the outer end of the head member, each with a plurality of gripping faces parallel to the longitudinal axis of the wrench for all positions of the jaw members, said gripping faces forming an angular recess in each of said jaws, a coiled spring mounted in the inner end of each socket so as to yieldingly hold the jaw members in extreme outward position, said sockets being so positioned that outward movement of the jaw members tends to open the jaws and inward movement of the jaw members tends to close the jaws, and a handle removably mounted on the inner end of the head member.

In witness whereof, I hereunto subscribe my name this 1st day of February, A. D., 1922.

ISRAEL C. GELLMAN.

Certificate of Correction.

It is hereby certified that in Letters Patent No. 1,451,873, granted April 17, 1923, upon the application of Israel C. Gellman, of Chicago, Illinois, for an improvement in "Adjustable Socket Wrenches," errors appear in the printed specification requiring correction as follows: Page 3, lines 10 and 23, claims 1 and 3, for the words "intersecting having" read *having intersecting*; same page, line 17, claim 2, for the word "member" read *members*; and that the said Letters Patent should be read with these corrections therein that the same may conform to the record of the case in the Patent Office.

Signed and sealed this 29th day of May, A. D., 1923.

[SEAL]

KARL FENNING,
Acting Commissioner of Patents.
